UNITED STATES PATENT OFFICE.

EDWARD MELDAL, OF LONDON, ENGLAND.

SEAT GUARD FOR WATER-CLOSETS.

Application filed November 21, 1922. Serial No. 602,397.

To all whom it may concern:

Be it known that I, EDWARD MELDAL, residing at London, England, a subject of the King of Great Britain and Ireland, have invented certain new and useful Improvements in Seat Guards for Water-Closets, of which the following is a specification.

This invention comprises a seat guard for water closets involving the use of a casing

10 containing a pack of guard sheets located behind the seat, each sheet having at one edge a tab whereby it can be drawn from the casing across the seat and made fast at the front edge. With this arrangement the 15 sheet while in use is held securely in position at the front by the fastening referred to, and at the rear by its attachment to the pack or casing.

20 A convenient device for the attachment of the sheet at the rear is a clip of stout wire having its ends bent at right angles to form two limbs, which are hinged to the board or ledge behind the seat, with springs tending to hold it down. For greater security 25 I may attach to the board a strip of rubber or equivalent material, preferably corrugated, against which the clip presses the sheet, or I may attach such material to the clip itself.

30 A convenient device for attaching the tab in front of the seat is a strip of rubber under which the tab can be pushed. For such strip of rubber I may use a V-shaped wire holder fixed under the seat, near the front 35 edge, and having its ends bent up so that they lie in front of the edge, with the rubber strip stretched between them.

When using a casing mounted behind the seat, and relying, for attachment of the 40 sheet at the rear, on its connection to the pack or the casing, it may be desirable to strengthen the rear edge of the sheet, or I may use a pack of sheets held together by means of a glued binding like the sheets of 45 a writing pad.

The tab at the front edge of the sheet may be utilized as a convenient means for ensuring that only a single sheet is withdrawn from the case. For this purpose the 50 tab on each sheet in the pack is either folded back against the front surface of the sheet, and is consequently separated from all the other tabs or the latter is so folded as to separate the tabs so that only one tab can be taken hold of, and only one sheet will be 55 withdrawn.

I provide the case with a cover in front, having at the bottom a hinged flap which can be lifted to give access to the tab of the sheet to be drawn out. Where this flap rests 60 on the side walls of the case, I may make these walls slope outwards, from top to bottom, so that the flap is somewhat inclined when closed. It then closes the case better 65 than when hanging down vertically.

For securing the pack in the casing I may use thin wire loops or rings at the top corners of the pack, hung upon hooks at the top of said casing. When using folded sheets, with the fold at the top, each of the 70 rings referred to passes through a double thickness of the sheet and in that case I may fold the sheet so that at the bottom the rear edge overlaps the front edge, and the rear edges of all the sheets are also furnished with wire rings, which engage hooks or pins at or near the bottom of the casing.

75 Embodiments of the invention are illustrated in the accompanying drawings in which, Fig. 1 is a perspective view of one 80 form showing a guard over the seat and the front cover of the casing partly raised. Fig. 2 is a cross section through the casing and sheets with the cover of the former completely raised. Fig. 3 is a front elevation 85 of the casing with the front removed and the walls in section. Figs. 4 and 5 are respectively plan view and side elevation of one form of clip for holding the guard sheet at the front. Figs. 6 and 7 are similar 90 views of another form of such clip. Figs. 8 and 9 are detail views of two forms of fastening devices for the lower ends of the pack of sheets; and Fig. 10 is a perspective 95 view of a sheet, for use with the form shown in Figs. 1 to 3, showing a method of folding same.

The form shown in the drawings comprises a box or casing α provided at the top with a hinged lid α^1 opening outwards or 100 backwards, to permit ready insertion of the stack of sheets and avoid contact with the usual flush pipe and furnished at the front with a hinged flap or cover α^2 extending for about half the height and hinged to be 105 opened upwards as by means of the knob α^3 . Such a casing with the pack of sheets β contained therein is adapted to be placed immediately at the rear of the seat c as shown in Fig. 1. The sheets are preferably 110 of the form and folded as more particularly shown in Fig. 13, that is to say each is

folded along a line b^x into two parts b^1 , b^2 , the front part b^1 being provided at its lower or forward edge with a projecting tab b^3 and with a flap tab b^4 extending inwards 5 from its aperture b^5 to protect the person from contact with the edge of the seat aperture.

The rear part b^2 extends lower than the general edge of the front part for a distance 10 approximating to the length of the tab b^3 and is provided near its lower edge with apertures b^6 , whilst at the top adjacent the fold both parts are provided with other apertures b^7 , said apertures being for the 15 passage of fastening means now to be described.

At the top, said fastening means comprise open ended rings or loops d as of thin wire, passed through the apertures b^7 and suspended from hooks d^1 attached to the inside of the casing and extending substantially across the width thereof. At the base other similar rings or loops d^2 are passed through the aperture b^6 and are held in 25 position by spring clips d^3 of which two forms are shown in Figs. 8 and 9 comprising bent wires or spring metal plates d^4 attached to the floor of the casing and bent over more or less at the ends as at d^5 , Figs. 30 8 and 9, or bent outwardly as at d^6 , Fig. 3, and of such length and width as to allow free play for the rings or loops d^2 therein except in a forward direction.

The pack of sheets thus mounted in the 35 casing a is ready for use and the method of folding described renders the tab b^3 of a single sheet only readily accessible when the flap or cover a^2 is raised as shown in Fig. 1 and permits the guard sheet to be 40 quickly and accurately drawn across the seat as also indicated in said figure the rear of such sheet being held by the loops d^2 and spring clips d^3 and restrained from complete unintentional removal by said loops 45 and by the hinged flap a^2 when the latter is lowered.

It now only remains to secure the sheet at the front when desired and this is performed by means of a clipping device either 50 of the form shown in Figs. 4 and 5 or in Figs. 6 and 7. The former comprises a plate e of spring metal attached as by screws to the underside of the front of the seat and provided with a curved metal backing plate 55 e^1 to which is attached a strip e^2 of corrugated rubber or some other resilient material, the forwardly extending end of the spring plate e being provided with a knob

or finger piece e^3 . In use the tab b^3 is passed around the front edge of the seat and gripped by the strip of rubber e^2 after depressing and releasing the spring plate e by means of the knob e^3 .

The form of clip shown in Figs. 6 and 7 is somewhat different and comprises a V-shaped piece of wire f looped at its apex to provide an aperture for passage of a fastening screw or stud f^1 . Connecting its bent up free ends is a double band f^3 of rubber or other resilient material to which is attached a tab f^4 preferably of or covered with corrugated rubber. In this case also the tab b^3 on the guard sheet is passed around the front edge of the seat after pulling out the band f^3 by its tab f^4 and on release will be securely clipped to the seat.

It will be apparent that the construction and arrangement of the casing a as above described will when the flap a^1 is closed protect the guard sheet against liquid which 80 may be spilled or accidentally reach the seat.

What I claim as my invention and desire to secure by Letters Patent of the United States is:—

1. A seat guard container for water closets comprising a casing for receiving a pack of guard sheets therein, means for detachably suspending said sheets in said casing comprising hooks secured to said casing and loops traversing the tops of the sheets and engaging said hooks, said casing being formed with an opening through which the detached sheets are withdrawn and a normally closed cover for said opening engaging said sheet to prevent the complete withdrawal of the same.

2. A seat guard container for water closets comprising a normally closed casing adapted to receive a pack of guard sheets therein, means at the top of said casing for detachably suspending said sheets, additional sheet securing means passing through said sheets arranged at the bottom of said casing, said casing being formed with an opening through which the sheets are withdrawn and a normally closed hinged cover for said opening extending below said additional sheet securing means and adapted to frictionally engage the sheet and co-operating with the additional sheet retaining means to prevent the complete withdrawal of the sheet from the casing.

In witness whereof I have signed this specification.

EDWARD MELDAL.
